UNITED STATES PATENT OFFICE.

FRANKLIN HOLLAND, OF GRAND RAPIDS, MICHIGAN.

CARVING-MACHINE.

SPECIFICATION forming part of Letters Patent No. 329,647, dated November 3, 1885.

Application filed October 21, 1884. Serial No. 146,000. (No model.)

To all whom it may concern:

Be it known that I, FRANKLIN HOLLAND, of Grand Rapids, in the county of Kent, and in the State of Michigan, have invented certain new and useful Improvements in Carving-Machines; and I do hereby declare that the following is a full, clear, and exact description thereof.

My invention relates to improvements in carving or ornamenting machines, and will be fully described hereinafter.

In the drawings, Figure 1 is a side elevation of a carving-machine embodying my invention. Fig. 2 is a vertical section through the center of the machine; and Fig. 3 is a sectional top plan view on line $x-x$ of Fig. 2.

A A' indicate the frame of my device, the horizontal arm A' of which has in the underside face of its outer end an annular slot, $a a$, whereon is loosely fitted the annular flange $b b$, formed in the upper face of the yoke B. This yoke is thus adapted to be freely swung in the supporting-frame, and is, moreover, held thereon in any adjustment desired by means 20 of any suitable clamping device, as shown at $b' b'$, between the outer wall and inner circular wall, a' , of A'. The yoke carries in its under side the bearing-boxes B' B², the upper halves of which are made integral with or 25 fastened to the said yoke, while the caps $b^2 b^3$ are fastened to the boxes in the usual manner. The rear cap, b^2 , is provided with a step, b^4 , having a screw-threaded perforation, wherein works the step-screw b^5 , designed to firmly 30 hold in position against the box B² the spindle C. This latter is provided between the bearing-boxes B' and B², in which it is journaled, with a flanged pulley, C', and this is connected with any driving mechanism through the belt 35 40 D, which passes upward into the circular opening made at A² in the rounded outer end of the arm A'. The spindle C is lengthened by

means of the center c , to the outer end of which may be fitted any one of the multiform cutters generally in use, as shown at c' .

It will be readily understood that by the arrangement described above the operator of the machine will be enabled to swing the spindle C in any direction in the plane in which the yoke B is hung in the frame, and 45 to hold the said spindle in the adjustment desired as long as is needed.

Having thus described my invention, what I claim as new, and desire to secure by Letters Patent, is—

1. In a carving or ornamenting machine, the combination of a horizontal supporting-arm having an annular groove in its under side, a yoke provided with an annular flange working in the arm-groove, and with vertical 60 adjusting clamp-bolts to hold the said yoke in any desired adjustment, and a spindle adapted to be rotated in box-bearings of the yoke, substantially as and for the purpose set forth.

2. In a carving or ornamenting machine, 65 the combination of the frame A, having horizontal supporting-arm A', with annular slot $a a$ on the under side, and central circular opening, A², the swinging yoke B, having annular flange $b b$, adjusting clamp-bolts $b' b'$, 70 and bearing-boxes B' B², with caps $b^2 b^3$, and step b^4 and step-screw b^5 , for adjusting the spindle, and the spindle C, carrying the pulley C' and its center c , with cutter c' , substantially as shown and described, and for the purpose 75 set forth.

In testimony that I claim the foregoing I have hereunto set my hand, at Grand Rapids, in the county of Kent and State of Michigan, in the presence of two witnesses.

FRANKLIN HOLLAND.
